UNITED STATES PATENT OFFICE.

JOHN E. BELL, OF BROOKLYN, NEW YORK, ASSIGNOR TO COMBUSTION ENGINEERING CORPORATION, A CORPORATION OF NEW YORK.

GRINDING AND DRYING APPARATUS.

Application filed January 12, 1922. Serial No. 528,669.

My invention relates to grinding and drying apparatus especially useful for preparing pulverized fuel such as coal that is to be burned in powdered form. I aim to make both the crushing or grinding and the drying operations rapid, continuous, efficient and economical, and to enable them to be carried on concurrently. I also aim to make the apparatus itself simple and compact, durable and rugged in service, and relatively inexpensive as regards both maintenance and initial cost. How these and other advantages can be realized through my invention will appear from my description hereinafter of the best forms of embodiment known to me.

Another type of apparatus embodying some of the underlying principles of the apparatus here shown and described is disclosed in my companion application, Serial No. 528,668, filed January 12, 1922.

In the drawings, Figs. 1 and 2 together show a vertical axial section through an apparatus conveniently embodying my invention,—Fig. 1 showing the fuel intake end of the apparatus, and Fig. 2 the discharge end.

Fig. 3 shows a transverse section through the apparatus, taken as indicated by the line 3—3 in Fig. 1.

Fig. 4 is a plan view of the apparatus, on a smaller scale than Figs. 1 to 3, showing the connections for supply or circulation of a heating (or cooling) medium.

Fig. 5 is an end view from the left of Figs. 2 and 4 (on a larger scale than Fig. 4), with parts in front of a plane of section indicated by the line 5—5 in Fig. 2 broken away and removed.

Figs. 6 and 7 together show a vertical axial section through another form of apparatus embodying my invention,—Fig. 6 showing the fuel intake end of the apparatus, and Fig. 7 the discharge end.

Figs. 8, 9 and 10 show transverse sections through the apparatus at various points, taken as indicated by the lines 8—8 and 9—9 in Fig. 6, and by the line 10—10 in Fig. 7.

The apparatus shown in Figs. 1, 2 and 3 comprises a horizontal rotary casing or shell comprehensively indicated by the numeral 11, in which the fuel is ground, dried, heat-

ed or cooled, as required. At its ends, the shell or drum 11 has hollow supporting trunnions or journals 12, 13, which are mounted to turn in water-cooled journal boxes or bearings 14, 15. The shell may be driven from any suitable source by means of a gear 16 keyed fast on the end of the journal 12. Fuel is fed into the drum 11 at its rotating journal 12 as intake, through a stationary conduit sleeve 17 provided with a receiving hopper 18, with the aid of a rotary feed screw 19. The feed screw 19 may be driven from any suitable source (preferably but not necessarily the same as that whence the drum 11 itself is driven) by means of a pulley 20 keyed fast on the end of the screw shaft. Its rate of revolution may preferably bear a suitable definite relation to that of the drum 11, according to the conditions of operation existing from time to time. The fuel entering the drum 11 by the journal 12 at the left-hand end (Fig. 1) is fed through grinding devices in the drum by the impulsion of that fed in after it, is crushed and ground to the desired degree of fineness by said devices, and is ultimately discharged by gravity from the drum through peripheral portage 22 at its right-hand end (Fig. 2). From the discharge ports 22, the fuel drops between external flanges 23 on the drum 11 that rotate in circular openings in the walls of a receiver or casing structure annularly circumjacent the ports 22, as indicated at 24, and substantially seal with said walls. A dust-tight joint is formed around the rotating flanges 23 by stationary packings 25, 25 on the casing 24 that run in peripheral grooves in said flanges.

The progressive breaking up of the fuel in grinding permits progressive liberation of such moisture as may be present in it. In order that full advantage may be taken of this favorable opportunity for drying the fuel, I prefer to provide for passing a drying medium over or through the fuel while being ground, to absorb or carry off the moisture,—preferably in a direction the reverse of that in which the fuel travels, so that the driest air comes in contact with the driest fuel. As here shown, air for this purpose enters the drum 11 at its right-hand end, through the upper portion of the casing 24

and the peripheral ports 22 that are uppermost as intake. After traversing the grinding devices in the drum 11, the moisture-laden drying air leaves the drum around the fuel taken in at its left-hand end, by peripheral portage 26 between flanges 27 that run in openings in a discharge casing 28, the joints being made tight by packings 29. The conduit 17 through which fuel is taken into the shell 11 is extended inwardly through a larger opening 30 in a frustro-conical diaphragm 31 at the inner side of the portage 26 so that the fuel cannot get into the air discharge.

15 Referring, now, to Fig. 3 as well as to Figs. 1 and 2, it will be seen that in the path of the fuel as it traverses the drum 11 are one or more (here a series of six) grinding devices, which in the present instance are of 20 a gravitational type, and counterparts of one another. As shown, each of these devices comprises a circular liner band or internal track 33 at the periphery of the drum and a tire-like annular member 35 adapted to 25 roll upright on said track, as the drum 11 revolves, under lateral guidance of inward projecting lugs or vanes 36, 36 at either side of the track. As the tire 35 thus rolls under the influence of gravity, it always remains substantially at the low point of the track 33. The track 33 should preferably be 30 of very hard steel (such as manganese steel), and the tire 35 of ordinary tire steel such as used for the tires of railway wheels. Preferably, the internal crushing or grinding surface of the track 33 is concaved, transversely, in the arc of a circle, and the external crushing or grinding surface of the tire 35 is made correspondingly and 35 centrically convex, to the same radius of curvature. Except at the center 37, the interior of the tire 35 and the casing 11 are 40 occluded by a transverse partition or web 38, extending inward from and across the inside 45 of the tire. By keeping the fuel from passing freely and directly across the internal periphery of the tire 35, the diaphragm 38 causes it to accumulate to such a depth on the interior of the drum 11 that as it is carried up with the revolving drum (with some 50 assistance from the lugs 36) it is crowded and directed across the internal track 33 and the periphery of the tire 35, through the gap that exists between them everywhere above 55 the low point of the track. Owing to the continual feeding in of the fuel at 12, this condition obtains to the left of every track 33 and tire 35. The fuel progressively crushed under the weight of the tires 35 is 60 fed across the track 33 and the inner surface of the tire by the pressure of fresh fuel continually entering between tire and track,— and in this manner, the fuel is fed across all the tracks in succession.

65 If the amount of fuel fed in exceeds the capacity of a grinding device, the excess will accumulate to such an extent as to overflow the diaphragm 38 and pass the tire or tires 35 thus affected uncrushed. If the excess input of fuel is of sufficiently short duration, 70 the fuel thus overflowing the left-hand diaphragms 38 will ultimately be crushed, nevertheless, by the tires 35 to the right. The central openings 37 in the diaphragms 38 not only afford by-passage for excessive 75 amounts of fuel from one track 33 to the next in the manner just described, but also afford passage for drying air additional to that between tires and tracks above the fuel, and thus assure free passage of air in 80 amounts fully adequate to absorb or carry the moisture from the fuel as it is progressively liberated.

To aid in drying the fuel, I prefer to heat it during grinding, or to heat the drying air, or both. Without excluding preheating of the drying air, I have in the present instance provided for heating the shell 11 as a means of heating both the fuel and the air. For 85 this purpose, the shell 11 is provided with a heating jacket, comprehensively indicated at 40, and provision is made for supplying or circulating a heating medium even while shell and jacket are in motion. As shown in 90 Figs. 1 to 3, shell 11 and jacket 40 are consolidated, so to speak, in a unitary double walled sectional construction. Besides the intake section 41 (with the shell end 42, the flanges 27 with their interconnecting webs 95 43, and the diaphragm 31) and the discharge section 44 (of similar construction, though without any homologue for the diaphragm 31), the casing 11 comprises a set of superposed counterpart hollow annular sections 45, one to each of the (six) grinding devices 33, 35. When assembled, these sections 45 are secured together and to the end sections 41, 44 by bolts 46 taking through external flanges 47 at the abutting faces of the sections. The inner wall of each section 45 100 has a shallow groove in which the annular track 33 is snugly seated, and securely held against lateral displacement by engagement with its shoulders. Each section 45 also comprises half of each of the guide lugs 36 105 that separate adjacent tires 35, and are also adapted to prevent lateral displacement of the track 33. In order that the track 33 may be absolutely integral and unbroken by joints (which would weaken it and tend to 110 produce very rapid wear), it is preferable to make each annular section 45 in (six) double walled arc sections or segments 48 (Fig. 3) that can be conveniently assembled 115 and secured together around the track. As shown, these hollow segments 48 intercommunicate, but are otherwise completely closed; they may be made tight with one another by the usual means, such as interposed 120 gaskets. It will be seen, therefore, that each 125 130

section 45 is individually jacketed, in that it has a separate annular jacket space of its own.

As a heating medium for the sectionally 5 jacketed rotary drum 11, I ordinarily prefer steam, on account of its lightness and high thermal capacity. For the purpose of supplying steam to the sectional jacket 40, the rotating hollow journal 13 at the right- 10 hand end of the shell 11 is extended beyond the bearing 15 through a stationary annular chamber 50 (Fig. 4) having a steam inlet 15 51. The journal 13 communicates with the chamber 50 through an annular series of ports 52 in the journal,—tight joints being insured by stuffing boxes 53 at either side of the chamber. At its other end, inside the bearing 15, the journal 13 is enlarged into a steam distribution chamber 54 whence 20 radiate (see Figs. 4 and 5) conduit means comprising a number of pipes 55 by means of which the journal is connected to the jackets in the several sections 45. As shown, there are six of these pipes, each connected 25 to one segment 48 of each annular jacket section 45.

For the purpose of relieving the sectional jacket 40 of water of condensation (and of air), a collection chamber 56 (Fig. 2) is 30 provided in the journal 13 inside the distribution chamber 54, and from it a drain or draw-off pipe 57 is led through the midst of the axial steam intake in the journal to a stationary elbow 58, provided with a stuffing box 59 to make a tight joint. The collection chamber 56 is connected to the jackets 45 by (six) pipes 60,—each of which is connected to one segment 48 of each 35 annular jacket. As shown, the pipes 55 and 60 extend through the flanges 27 with a close fit and across the intervening space. To insure flow of the water through the conduit means 60, 56, 57 each of them is first led helically around the shell 11, clockwise 40 (Figs. 3 and 5) from the furthest section 45 to the discharge section 44, and connected successively to the successive segments 48 of adjacent sections 45. Beyond the discharge 45 section 44, each pipe 60 is led spirally inward clockwise to the collection chamber 56. Counterclockwise revolution of the shell 11, therefore, will cause the water to flow by gravity from the jacket sections 45 to the collection chamber 56, and on out through 50 the pipe 57.

If the material being crushed or ground is of such a nature that the operation tends to heat it or the apparatus objectionably, a cooling medium (cold brine, for example) 55 may be circulated through the jacket 40. In the case of a liquid medium, the liquid in the several pipes 55 will always be balanced as regards gravitation, so that circulation of the liquid in one direction or the other 60 through the jacket and piping system will

result from the influence of gravity on the liquid in the pipes 60 as the drum 11 is rotated either clockwise or counterclockwise.

The apparatus shown in Figs. 6 to 10 differs from that just described in various 70 particulars, the more important of which may be briefly indicated. In Figs. 6 to 10, various parts and features substantially like corresponding features in Figs. 1 to 5 have been marked with the same reference numerals, as a means of avoiding merely repetitive description.

The casing, shell, or drum 71 is driven by an electric motor 72 whose shaft is coupled to a pinion 73 meshing with a large gear 74 80 bolted directly to the intake end 75 of the drum. At the discharge end 76, the webs 77 interconnecting the flanges 26 extend radially instead of circumferentially. While the intake of fuel and of drying medium, (air) and the discharge of fuel are substantially the same as in Figs. 1 to 3, the discharge of drying air is effected somewhat differently,—through a stationary chamber 78 that communicates with an annular passage 79 around the fuel conduit 17 within the journal 12.

The crushing or grinding devices in the shell 71 differ from those of Figs. 1 to 3 in several particulars. On each internal track 95 are a plurality of tires, rolling one within another,—only the innermost having the occluding diaphragms 38. The tires are guided (and adjacent ones separated) by arcuate bars 80 (preferably of cast steel), here arranged in "polygonal" (triangular) sets at either side of each annular track, adjacent bar ends having overlapping feet 81 through which extend bolts 82 that secure them to the drum 71. The corners of the 100 guide bars 80 are bevelled, so as to enable them to coact with the edges of the tires in crushing such material as may get between. The tracks 83 toward the fuel intake 12 (Figs. 1, 8 and 9) are not truly circular or integral, but polygonal faced, and composed of a multiplicity of flat-faced, arcuate-backed segments 84 secured against the interior of the shell by bolts 85 whose 105 heads 86 are counter-sunk and preferably 110 covered over with zinc, as shown at 87 in Fig. 8. The exteriors of the tires 88 and 89 are circular, as in Fig. 3; but the interior or inner face of the intermediate tire 88— 115 which serves as track to the smaller dia- 120 phragmed tire 89 within it—is polygonal (though integral), like the track 83 itself. This polygonal track form is of advantage for the initial coarse crushing, since it allows the finer particles of fuel to cross the track with some degree of "impunity," so 125 to speak, so that the weight of the tires is more or less concentrated on the larger pieces. The tracks 90 (Figs. 2 and 10) toward the discharge end of the shell 71 are 130

circular faced (though segmental), so as to enable the intermediate tires 91 to crush the fine particles effectually, and the interiors or inner faces of these intermediate tires 91 are likewise circular.

As indicated in Figs. 1 and 9, one of the tracks 83^a and its tires 88^a and 89^a may combine the concave and convex tread conformation of Figs. 1 to 5 with the polygonal form of Figs. 8 and 9.

The shell 71 is not sectional, but, on the contrary, consists of a couple of stout concentric metal cylinders or shells 92, 93 with heating jacket space 94 between them. At 15 each of the bolts 82 and 85 a shouldered spacer 95 (preferably of cast steel) is interposed between the drums 92 and 93. Its reduced outer portion extends through the outer shell 93 and "takes" the double nuts 20 on the bolt. The edges of the spacer 95 may be welded to the shell 92, and the edges of the reduced portion may be welded to the shell 93,—for the sake of greater strength and fluid tightness. It will be seen that in 25 this apparatus the shells 92, 93 are largely relied on to give the tracks 83 and 90 the required strength. The opposite ends of the shells 92, 93 are separated by annular lateral flanges 98 and 99 bolted to the end 75 and 30 to the adjacent discharge flange 23, respectively, and are riveted to said flanges.

Steam for heating the shell 71 is supplied the jacket by the hollow journal 13, through a pipe 100 that revolves in a stuffing box in 35 a stationary fitting 101 and thence extends inward to a three-way fitting 102 in the interior of this axial steam intake 13. From the fitting 102 radiate pipes 103 that extend across the fuel and air discharge through 40 hollow thickened portions 104 of the webs 77, and are connected to the adjacent end of the jacket 94. Water of condensation may be drawn off at each revolution by means of a balanced discharge valve 45 105 biased toward closing by a helical compression spring 106, and actuated by a crank arm 107 pivoted to a bracket arm 108 on the valve casing. The arm 107 carries a contact roller 109 which at each revolution of the valve with the shell 71 may 50 wipe against a cam track 110 mounted and adjustable in a bracket 111, so that it may be set in or out of the path of the roller,—or adjusted to regulate the length of time the 55 valve 105 will be open according to the average amount of water to be got rid of. The blow-off valve 105 may discharge into a trough or funnel 112 on a drain pipe 113.

What I claim is:

60 1. A continuous grinding and drying mill comprising a rotary casing with grinding means therein and peripheral portage at one end, and stationary casing means arranged annularly about said portage and 65 substantially sealing with the rotary casing

above and below at either side of said portage, for discharge of ground material from the rotary casing below and passage of a medium for drying such material above.

2. A continuous grinding and drying mill 70 comprising a rotary casing, with intake for material to be ground and with discharge for drying medium, one around the other, and also with discharge and intake means for such material and such medium, respectively, affording peripheral portage for discharging the material when ground; gravitational grinding means in said casing; and means for feeding material to be ground into said casing by the corresponding intake and through said grinding means to said discharge portage.

3. A continuous grinding and drying mill 80 comprising a rotary casing, with hollow journal means for intake of material to be ground, and with peripheral discharge means; grinding means in said casing; and means for discharge of drying medium from said casing around the material entering 90 at said journal means.

4. A continuous grinding and drying mill comprising a rotary casing with hollow journal means for intake of material to be ground at one end and with peripheral discharge means at the other end, and with intake for drying medium; a series of internal tracks in said casing in the path of the material therethrough, and rotary tires adapted to roll on said tracks as the casing revolves; means occluding the interiors of said tires except at their centers, to prevent material from passing directly across their internal peripheries; and means for discharge of drying medium from said casing around the material entering at said journal means. 100

5. A continuous grinding and drying mill 110 comprising a rotary casing with grinding means therein; means for feeding material to be ground through said casing and its grinding means, means for passing drying medium through said casing to absorb moisture liberated from said material in grinding; and means for heating the material during grinding. 115

6. A continuous grinding and drying mill comprising a rotary casing with a heating jacket and grinding means therein; means for feeding material to be ground through said casing and its grinding means; means for passing drying medium through said casing to absorb moisture liberated from said material in grinding; and means for passing a heating medium through said jacket while revolving with said casing. 120

7. A continuous grinding and drying mill comprising a jacketed rotary casing with grinding means therein, hollow journal means for intake of material to be ground at one end and for passage of heating 125

- medium for the jacket at the other end, peripheral portage at said latter mentioned end for discharge of ground material and passage of drying medium to absorb moisture liberated from the material in grinding, and means for passage of drying medium around the incoming material to be ground at the first-mentioned end. 5
8. A continuous grinding and drying mill comprising a jacketed rotary casing with grinding means therein, hollow journal means for passage of material to be ground at one end and of heating medium for the jacket at the other end, means for discharge 10 of ground material at said latter-mentioned end, and means for passing a drying medium through said casing and its grinding means counter to the travel of material being ground, to absorb moisture liberated 15 from the latter. 20
9. A continuous grinding and drying mill comprising a rotary casing with intake for material to be ground and discharge for drying medium, one around the other, and 25 discharge and intake means for such material and such medium, respectively affording peripheral portage for the former; gravitational grinding means in said casing; and means for heating the material during grinding. 30
10. A continuous grinding and drying mill comprising a jacketed rotary casing with hollow journal means for intake of material to be ground at one end and intake means 35 for drying medium at the other end, and at the latter mentioned end peripheral discharge means for ground material and hollow journal means connected with the casing jacket for supplying heating medium thereto; a series of internal tracks in said casing 40 in the path of the material therethrough; and rotary tires adapted to roll on said tracks as the casing revolves and crush the material traversing them. 45
11. A continuous grinding and drying mill comprising a jacketed rotary casing having hollow journal means at one end and peripheral portage means at the other, and also having discharge means for drying 50 medium and hollow journal means at the aforementioned ends of said casing, respectively; grinding means in said casing; means for feeding material into said casing by one of the means first-mentioned and 55 through said grinding means to the other of said first-mentioned means; and means for supplying heating medium to the casing jacket by the hollow journal means at the same end of the casing as said peripheral portage means. 60
12. A sectional grinding and drying mill comprising a set of superposed annular sections secured together and having internal tracks for the rolling of rotary tires as the 65 mill revolves; a section secured to one end of the set having hollow journal means for intake of material to be ground and also discharge means for drying medium; and a section secured to the other end of the set having peripheral discharge for ground material and axial intake for heating medium, with means of connection from said latter intake to said heating jackets. 70
13. A grinding and drying mill casing comprising end sections with intake and discharge means, and a jacketed intermediate portion comprising an internal grinding track and a double walled shell therearound, one of said last-mentioned parts being continuous and the other in segmental sections. 75
14. A grinding mill casing comprising a plurality of superposed annular sections secured together, including end sections having intake and discharge means, and intermediate sections having internal tracks for the rolling of rotary tires as the casing revolves and individual heating jackets for such sections surrounding said tracks. 80
15. A unitary casing section for a rolling tire grinding and drying mill, adapted to be secured to other casing sections at either side, and comprising in the one unitary structure an internal track for the tire, 85 guide means for the tire beside the track, and a heating jacket surrounding the track. 90
16. A unitary casing section for a rolling tire grinding mill, comprising in the one unitary structure an internal track for the tire and a separate shell portion about said track carrying means for preventing lateral displacement of the track and lateral guide means for the tire, and also provided with means for securing the section in assembly 95 with laterally adjacent casing sections. 100
17. A grinding mill comprising a rotary casing with internal tracks, and rotary tires adapted to roll on said tracks as the casing revolves, the first of such track and tire grinders in the path of the material having a polygonal faced member, so as to permit relatively fine particles to pass it freely, and the last comprising circular faced members for grinding such particles. 105
18. A grinding mill comprising a rotary casing with a polygonal surfaced internal track; and a rotary tire adapted to roll on said track as said casing revolves. 115
19. A grinding mill comprising a rotary casing with a polygonal surfaced internal track; and a circular rotary tire adapted to roll on said track as said casing revolves. 120
20. A grinding mill comprising a jacketed rotary casing with grinding means and with hollow journal means for intake of a medium circulating through the jacket, and means of connection between said journal and said jacket comprising a conduit extending helically around said casing from its jacket connection toward its journal. 125
21. A grinding mill comprising a rotary casing with a polygonal surfaced internal track; and a circular rotary tire adapted to roll on said track as said casing revolves. 130

connection, and spirally inward to said journal means.

21. A grinding mill comprising a jacketed rotary casing with grinding means and with 5 hollow journal means for intake of a medium circulating through the jacket, and means of connection between said journal and said jacket comprising a conduit extending helically around said casing from 10 its jacket connection toward its journal connection.

22. A grinding mill comprising a jacketed rotary casing with grinding means and with 15 hollow journal means for intake of a medium circulating through the jacket, and means of connection between said journal and said jacket comprising a conduit

extending inward spirally between its jacket connection and its journal connection.

23. A grinding mill comprising a plurality of superposed individually jacketed annular casing sections secured together, with hollow journal means for intake of a medium circulating through the jacket; 25 grinding means in the casing formed by said sections; and means of connection between said journal and said jackets comprising a conduit extending helically around said casing connected to the several jacket sections. 30

In testimony whereof, I have hereunto signed my name.

JOHN E. BELL.
